GUN MOUNTING ADAPTED TO BE DIVIDED
INTO SEPARATE LOADS

Heinrich Herlach, Solothurn, Switzerland, assignor to Waffenfabrik Solothurn A.-G., Solothurn, Switzerland, a corporation of Switzerland

Application November 27, 1933, Serial No. 699,998
In Germany December 30, 1932

5 Claims. (Cl. 89—40)

In the case of gun mountings which are intended to be dismantled for transport into units suitable for separate loads, care must be taken to ensure that the dismounting and also the reassembling of the gun mounting for firing can be carried out as rapidly and as safely as possible. The carrying out of these measures, particularly in the case of modern mountings for machine guns of 2 cm. calibre or more, is hindered by the elevating and traversing gear which in the form of gear mechanism connect one unit with another, for instance, a gun carrying saddle unit and a base unit supporting the saddle unit.

The object of the invention is to simplify the separation and assembly of the units while taking into consideration such mechanical connections as are provided for instance for traversing the gun and adjusting the sights, to such an extent that when the gun mounting is taken apart the gearing can also be separated without any special manipulation, so that the possibility of damage is greatly reduced, and, particularly when assembling the gun mounting, it is no longer necessary to maintain a definite coupling position for the parts of the gearing.

For this purpose, according to the invention, the gun aiming gearing, divided in a manner known per se, between two units such as a gun saddle unit and a base unit as aforesaid, is provided with shaft portions abutting against each other and each associated with a different unit, said shaft portions contacting at a plane of separation of the units and having flexible coupling members which when the gun mounting is assembled also bring about automatically the connection of the gearing. Furthermore, at least one of the two coupling members of a pair is movable from its position engaging the corresponding member against the action of a spring, to the extent necessary for disengagement. This makes it no longer necessary to ensure an exact coupling position at the time the units are assembled. When the units are assembled, if the shaft portions do not lie in the angular relationship to each other permitting the coupling members immediately to engage, one of them can yield owing to the presence of the spring and will remain retracted until, by a subsequent turning of a shaft portion, the coupling members come into register and re-engage, by the spring action. Such a detachable connection of the elevating and traversing gear in the plane of separation of the saddle and base units also permits a rapid lateral adjustment of the saddle by hand, independently of the traversing gear, if, accord-

ing to a further feature of the invention, the coupling claws protruding beyond the plane of sliding contact are adapted to be fixed in a "flush" or withdrawn position with respect to the sliding surface.

An example of construction of a gun carriage according to the invention is shown in the accompanying drawing, in which Fig. 1 is a side view of the gun mounting assembled for firing and Fig. 2 is a vertical section on an enlarged scale of the appropriate traversing gear.

The saddle 3, which carries the gun in such a manner as to allow it to be pivoted about a horizontal axis, is mounted so as to be capable of turning about a vertical axis through 360°, that is to say in a circle, on a fixed base 1 by means of a pivot member 2 adapted to turn therein. The saddle 3 is secured in known manner against upward movement on the pivot member 2 by an easily detachable screw connection 2', 3' or the like. After the detachment of such connection the saddle 3 is connected with the pivot 2 or the head 1 only by way of the gear members of the traversing gear and one which influences the clinometer sight 7. The hitherto known and usual construction of the gun mounting is rendered suitable for a rapid and safe dismantling into separate units and safe reassembly, by the particular transverse division of the elevating gear which permits an unhindered removal of the unit including the saddle.

To the base 1 there is firmly connected an annular gear wheel 4. This gear engages a pinion 6 which revolves in planet fashion and is adapted to be rotated by means of the traversing gear. The said pinion 6 is mounted in a bearing 5 which is arranged on a protecting ring 5' for the gear wheel 4, said ring being connected with the pivot member 2. Further, connected firmly to the base 1 is a gear wheel 4' which acts on the clinometer sight 7, and with which gear wheel there engages the pinion 6' which also is mounted on the pivot member 2. The driving shaft of the pinion 6 and the driving shaft of the pinion 6' are each divided transversely. At the point of separation each of the short shaft ends of the two pinions 6, 6' is provided with a frustoconical groove 9 or 9' in which the shaft ends 8 or 8' of the elevating gear engage by means of suitably shaped coupling dogs. The shaft ends 8, 8' are mounted so as to be axially displaceable and are pressed constantly into the coupling position by springs 10, 10', so that after the gun mounting has been assembled they spring automatically into engagement with the shafts of the pinions 6, 55

6' when the saddle 3 assumes the correct coupling pivotal-position in respect of the pivot member 2.

The shaft ends 8, 8' are prevented from turning with respect to their corresponding gears in like manner, the one by a sliding spring 10 and a groove 11 in the worm wheel 12, the other by a key 13 and a groove 13' in the bush 14. The worm wheel 12 is turned by a worm 15, which in its turn is driven by the hand wheel 17 through a mechanism 16 for more rapid or slower lateral swinging. In the bush 14 which is rotatably mounted in the bush 18 connected firmly to the saddle and on the rotation of the pinion 6' is carried along by the coupling shaft 8', there is soldered a flexible shaft 19 which serves to actuate the clinometer sight 7, so that all traversing movements of the gun carriage are communicated to the clinometer sight 7.

Owing to the fact that they can be displaced axially, the coupling shafts 8, 8' are displaced automatically from their coupling position in which they project beyond the plane of separation, when, on the assembly of the saddle and base units, the coupling position of the divided gear shafts 8-6 or 8'-6' is not attained at the outset, either because the centre axes of the separated halves do not run in line, or because the coupling notches 9, 9' are displaced in respect of the coupling dogs.

The transverse separation of the driving shaft 8 of the traversing gear, owing to the possibility of the coupling connection 9 being disconnected by hand, also permits a free swinging of the gun cradle. In the upper end of the shaft 8 there is screwed in a headed screw 20, the head 20' which rests on a handle 21 adapted to be turned about the coupling shaft 8. This handle rests with the opposite surface on the housing cover 22. The contact surface of the two parts 21, 22 lies in two parallel planes which are connected by a bevel surface 23. On being turned the lever 21 runs over the inclined surface 23, so that its lower supporting surface comes into position on the upper surface of the cover 22. The screw 20 causes the raising of the coupling bolt 8 by this change in height, so that its coupling dog is disengaged from the notch 9 of the pinion 6. The coupling bolt 8 thereby compresses the coupling spring 10 which is held by a pin 24 in the worm wheel 12 which at the same time forms the axial guide for preventing a turning movement of the bolt 8 during this adjustment. The compression of the spring 10 secures the handle 21 in the adjusted position against an involuntary backward turning.

To return to the traversing position for operation by means of the gun training mechanism, the lever 21 must be reversed, then the coupling bolt 8, under the influence of the spring 10, engages in the notch 9 of the pinion 6. If, as will be the case in consequence of the rotation of the pinion 6 which idles about the gear wheel 4 during the free lateral swinging movement, the notch stands offset in relation to the coupling member, the coupling will spring in automatically as soon as the coupling position has been attained by a short manipulation of the elevating gear.

I claim:—

1. In a gun carriage dismountable for transport into units including a saddle unit in which the gun is mounted and a base unit in which the saddle unit is supported, and having gun aiming mechanism associated partly with the saddle unit and partly with the base unit; the arrangement that the gun aiming mechanism comprises separable shaft portions, one in each unit, and in abutting contact with each other at a plane of division of said units when they are assembled, coupling means on the shaft portions at the place of contact, said coupling means being adapted to interlock with each other in a definite angular relationship of the shaft portions, and yielding means in one of the units for urging the corresponding shaft portion towards the other shaft portion and permitting assembly of the units independently of the angular relationship of the shaft portions.

2. In a gun carriage dismountable for transport into units including a saddle unit in which the gun is mounted and a base unit in which the saddle unit is supported, and having gun aiming mechanism associated partly with the saddle unit and partly with the base unit; the arrangement that the gun aiming mechanism comprises separable shaft portions, one in each unit, and in abutting contact with each other at a plane of division of said units when they are assembled, coupling means on the shaft portions at the place of contact, said coupling means being adapted to interlock with each other in a definite angular relationship of the shaft portions, and yielding means in one of the units for urging the corresponding shaft portion towards the other shaft portion and permitting assembly of the units independently of the angular relationship of the shaft portions.

3. In a gun carriage dismountable for transport into units including a saddle unit in which the gun is mounted and a base unit in which the saddle unit is supported, and having gun aiming mechanism associated partly with the saddle unit and partly with the base unit; the arrangement that the gun aiming mechanism comprises separable shaft portions, one in each unit, and in abutting contact with each other at a plane of division of said units when they are assembled, coupling means on the shaft portions at the place of contact, said coupling means being adapted to interlock with each other in a definite angular relationship of the shaft portions, yielding means in one of the units for urging the corresponding shaft portion towards the other shaft portion and permitting assembly of the units independently of the angular relationship of the shaft portions, and manually operable means for retracting the shaft portion acted upon by the yielding means sufficiently away from the other shaft portion to disengage the coupling means.

3. In a gun carriage dismountable for transport into units including a saddle unit in which the gun is mounted and a base unit in which the saddle unit is supported, and having gun aiming mechanism associated partly with the saddle unit and partly with the base unit; the arrangement that the gun aiming mechanism comprises separable shaft portions, one in each unit, and in abutting contact with each other at a plane of division of said units when they are assembled, coupling means on the shaft portions at the place of contact, said coupling means being adapted to interlock with each other in a definite angular relationship of the shaft portions, yielding means in one of the units for urging the corresponding shaft portion towards the other shaft portion and permitting assembly of the units independently of the angular relationship of the shaft portions, and manually operable means for retracting the shaft portion acted upon by the yielding means sufficiently away from the other shaft portion to disengage the coupling means and for retaining the said shaft portion thus retracted.

4. A gun carriage arrangement according to claim 1, in which one shaft portion has a transverse groove and the other shaft portion has a corresponding projecting tongue in the abutting surfaces of the shafts.

5. A gun carriage arrangement according to claim 1, in which the gun aiming mechanism comprises elevating gearing and traversing gearing, both including separable shaft portions provided with coupling means and yielding means.

HEINRICH HERLACH.
